UNITED STATES PATENT OFFICE.

AUGIE L. HANSEN, OF EVANSTON, ILLINOIS, ASSIGNOR TO JUSTRITE MANUFACTURING COMPANY, OF CHICAGO, ILLINOIS, A CORPORATION OF ILLINOIS.

PORTRABLE ACETYLENE-LAMP.

1,161,209.

Specification of Letters Patent.

Patented Nov. 23, 1915.

Application filed May 20, 1911. Serial No. 628,576.

To all whom it may concern:

Be it known that I, AUGIE L. HANSEN, citizen of the United States, residing at Evanston, in the county of Cook and State of Illinois, have invented certain new and useful Improvements in Portable Acetylene-Lamps; and I do hereby declare the following to be a full, clear, and exact description of the invention, such as will enable others skilled in the art to which it appertains to make and use the same.

My invention has for its object to provide a simple and efficient miner's acetylene gas lamp adapted to be worn upon the cap, and consists in the features of construction and combinations of parts hereinafter fully described and claimed.

In the accompanying drawings illustrating the invention: Figure —1— is a perspective view showing a miner's cap equipped with an acetylene lamp constructed in accordance with my invention. Fig. —2— is a central vertical longitudinal section of a lamp constructed in accordance with my invention showing the same mounted upon the lamp-carrying member of a miner's cap, the latter being also shown in section. Fig. —3— is a fragmentary detail horizontal section on the line 3—3 of Fig. 30 —2—.

My invention has for its particular object to provide an efficient, economical miner's lamp, the water-chamber of which has one wall constituting a reflector and through which the burner projects centrally.

A further object of the invention is to provide simple and efficient means for attaching and detaching the gas generating member of the lamp from the water chamber and providing means for controlling the flow of water from the latter to the former.

A further object of the invention is to provide simple and efficient means for firmly attaching the lamp to a miner's cap so as to prevent swaying of the same thereon or easy dislodgment therefrom.

Other objects of the invention will appear from the following description.

The lamp comprises a carbide receptacle 1 open at its upper end and terminating at said end in a threaded neck 2 of smaller diameter than the lamp-body and between which and said lamp-body an annular shoulder 3 is formed upon which the gasket 4 seats. The said lamp-body 1 is provided

with an inverted dished bottom 5 provided centrally within said receptacle with an annular perforated flange 6 which is adapted to receive the lower end of a tube 7 which is provided with longitudinal slots 8 extending from said lower end thereof to a point adjacent the upper end thereof. The said carbide receptacle 1 is adapted to be secured to a water receptacle or chamber 9 which consists of a horizontally disposed cylinder having one end wall or head 10 forming a reflector for the jet of flame projected from the burner 11 which projects centrally from said head or reflector 10. The said cylinder 9 is equipped at one side with a threaded cap member 12 adapted to receive the threaded neck 3 of the carbide receptacle 1, the said cap member being provided at its outer end with an annular flaring flange 13 between which and said shoulder 3 the said gasket 4 is adapted to be compressed to form a fluid-tight joint between said carbide receptacle and said cap member. The said cap member is mounted in an opening in the circumferential wall of the cylinder 9 and secured by means of solder, or the like, to form a fluid-tight joint therewith. The inner wall or head 14 of said cap member 12 is dished and presents a concave face to the interior of said cylinder 9. In said dished portion 14 of said head is a central opening which is surrounded by a small tube 15 soldered or otherwise secured and projecting outwardly therefrom and through which water is adapted to pass from said cylinder 9 into the carbide receptacle 1. The said central opening in said dished head 14 is controlled by a valve 16, the shank of which is enlarged and threaded at its upper end portion, as at 17, and is provided with a knurled head 18 by means of which said valve is turned. The said threaded portion 17 of said valve engages a threaded sleeve 19 mounted in the circumferential wall of the cylinder 9 diametrically opposite the said dished head 14 of the cap member, there being only about two threads on said enlarged portion of said valve so that the same may be easily disengaged from said sleeve and reciprocated for purposes hereinafter set forth. A small rod or wire 20 almost equal in diameter to the inner diameter of the tube is secured to the lower end of said valve and passes through the said tube 15, being adapted to be reciprocated to keep the latter clear of obstructions 110

to prevent interference with the flow of water therethrough and serving also to so far choke said tube as to insure a very slight flow of water therethrough. Water is admitted 5 to said cylinder 9 through the flanged opening 21 in the circumferential wall of the cylinder 9 disposed adjacent said sleeve 19 and which is closed by means of a screw cap 22 having a small opening 23 therein 10 through which air is admitted to said cylinder 9 or escapes therefrom. One end of a chain 24 is secured in a suitable manner to said cap 22 and at its other end carries a bar 25 of greater length than the diameter of 15 said flanged opening and is adapted to prevent the loss of said cap 22 when the latter is temporarily removed for the purpose of filling said receptacle 9 with water.

The gas generated within the carbid receptacle 1 by contact of water with the contained carbid is adapted to pass through a tube 26 mounted at one end in an opening in the dished head 14 of said cap member 12 and passing at its other end through a central opening in the dished head or reflector 10 of said cylinder 9, said tube being secured with said respective openings by soldering or similar means. Filtering material, such as cotton indicated at 27, is disposed in the mouth of a tube 26 so that the gas passing into the tube from the receptacle 1 will be freed of solid particles which are frequently carried thereby.

The miner's cap 28, shown in Fig. —1—, is provided with a visor 29 of a stiff material to which is secured one flange 30 of a plate 31, the latter being equipped at its other end with a flange 32 secured by means of rivets 33 to the crown of the cap 28. The 35 said flange 32 is provided with a perforation 34 and with a slot 35, the latter extending downwardly into the plate 31. On the rear wall of the cylinder 9 there is secured a cross-bar 36 provided at its ends with flanges 40 37 which are bent between their ends to render them substantially V-shaped, the apexes of the V's thus formed opposing each other and being separated by a space of less width than the plate 31 so that said flanges may be 45 sprung into engagement with said plate in a well-known manner. A vertical bar 38 also secured to the rear wall of the cylinder 9 terminates at its upper end in a hook 39 which is provided at its free end with a projection 40 adapted to be passed through the 50 said perforation 34, the body portion of the hook being adapted, after said projection 40 has been so passed through said opening and the lamp body then swung so as to engage the plate 31 between said flanges 37 of the cross-bar 36, to engage the walls of the slot 35. The lamp when so mounted upon the cap is rigid therewith and incapable of movement in any direction relatively to the 55 same.

The operation of the lamp will doubtless be understood from the foregoing description but for purposes of convenience a brief description thereof will be given. The carbid chamber 1 is filled about one-half 70 full of desiccated carbid and the water chamber 9 filled about one-half or two-thirds full of water, the valve 16 being closed at this time. The carbid receptacle 1 is then secured to the water chamber 9, as indicated, 75 and then upon slightly opening said valve 10, water is admitted to the carbid receptacle 1 drop by drop. The drops of water admitted to the carbid receptacle fall upon the middle portion of the dished bottom 5 thereof and flow toward the outer circumferential wall of said receptacle through the perforations in the said annular flange 6 mounted upon the middle portion of said dished bottom thus coming into contact with the carbid and generating acetylene gas. The gas generated causes a pressure to be developed within the carbid receptacle which resists the flow of more water through the valve opening thus automatically shutting off such flow until the gas pressure has been reduced to a point less than sufficient to overcome the water pressure whereupon a further drop or drops will pass into said carbid receptacle thus generating further gas. 95 The generated gas passes out through the tube 26 and burner 11. If at any time, the quantity of water admitted is so great as to cause an excessive generation of gas the resulting increase in pressure will cause said 100 gas to escape partially through the valved opening into the water chamber whence it will pass out through the vent opening 23 in the cap 22.

In order to render the cleansing of the 105 carbid chamber very convenient the tube 7 is rendered removable. The slotting of the lower end portion of said tube renders snug engagement of the same with the annular flange 6 possible, as will be obvious and 110 serves to permit water to escape freely therefrom into contact with the carbid. At the same time said tube serves to prevent the slaked lime resulting from decomposition of carbid from coming into contact with and closing the discharge end of the tube 15. The wire 20 carried by the valve serves, as will be obvious, to maintain said tube 15 clear of obstructions besides partially choking the same so as to prevent excessive flow 115 of water therethrough.

My said lamp affords a particular advantage in that the reflector constitutes one 120 head of the water chamber and is protected at its edges from contact with obstructions which generally, sooner or later, cause such reflectors to become loosened from the lamp body. The reflector is essential to the efficiency of the device for miner's use as it 125 concentrates a large proportion of the rays 130

upon the point at which the miner is working. Thus also the fastening means which I have provided are very advantageous in that they prevent the lamp from swinging relatively to the cap and thus insure concentration of the rays upon the desired point besides preventing the lamp from accidentally disengaging itself from the cap and dropping upon the floor where injury to it is easily possible. My said lamp is very efficient and economical.

I claim as my invention:

1. In a device of the character described a horizontal water chamber of cylindrical form, one end of the said cylinder being a reflector, a thimble secured in the lower part of the cylindrical wall having a closed concave top, threads rolled on its side wall, there being an opening in the center of said top and a carbide receptacle provided with threads which fit said first-named threads.
2. In an acetylene lamp, a reflector which constitutes an end wall of a horizontal cylindrical water receptacle, the entire surface of which is in contact with water, a thimble secured to the lower part of the cylindrical wall having a closed concave top, threads

rolled on its side wall, there being an opening in the center of said top, and a carbide receptacle provided with threads which fit 30 said first-named threads, the said threads extending up into the water chamber.

3. In an acetylene lamp, a reflector which constitutes an end wall of a horizontal cylindrical water receptacle, the entire inner 35 surface of which is in contact with water, there being a gas outlet located in the center of said end wall, and a tube leading therefrom to a gas chamber, the lower part of the cylindrical wall being formed with a circular hole, a thimble secured therein having a closed concave top, threads rolled on its side wall, there being an opening in the center of said top and a carbide receptacle provided with threads which fit 40 said first-named threads.

In testimony whereof I have signed my name in presence of two subscribing witnesses.

AUGIE L. HANSEN.
